[57] CLAIM

The ornamental design for a combined baseball hat bottle
opener and key chain holder, as shown and described.

DESCRIPTION

FIG. 1 is a top left side perspective view of a combined
baseball hat bottle opener and key chain showing our new
design;

FIG. 2 is a left side view thereof, the undisclosed right side
view being a mirror image thereof;

FIG. 3 is a front view thereof;

FIG. 4 is a bottom view thereof;

FIG. 5 is a top view thereof; and,

FIG. 6 is a back view thereof.
